UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FILLING-REPLENISHING-LOOM BOBBIN-SEPARATOR.

1,369,485.

Specification of Letters Patent. Patented Feb. 22, 1921.

Application filed December 24, 1919. Serial No. 347,104.

To all whom it may concern:

Be it known that I, MELVIN L. STONE, a citizen of the United States, residing at Lawrence, in the county of Essex and State 5 of Massachusetts, have invented an Improvement in Filling-Replenishing-Loom Bobbin-Separators, of which the following description, in connection with the accompanying drawings, is a specification, like 10 characters on the drawings representing like parts.

This invention relates to filling replenishing looms, and more particularly to means for separating substantially full and sub- 15 stantially empty filling carriers or bobbins as they are ejected from the shuttle.

In filling replenishing looms it is now the common practice to transfer a filling carrier having a supply of filling thereon from 20 a hopper to the shuttle and eject the filling carrier in the shuttle when such filling carrier is substantially exhausted of filling. This operation is referred to as replenishing the filling. In this general type of loom 25 the ejected filling carriers are thrown into a receptacle or container, and then the filling on the ejected filling carriers is removed and forms waste. The amount of waste, of course, will depend on the amount of filling 30 remaining on the filling carrier or bobbin when it is ejected from the shuttle, and looms of this character seek to minimize the amount of filling remaining on the filling carriers when ejected from the shuttle, with- 35 out, however, making partial or mis-picks.

It happens at times that filling replenishment is called by the filling detecting mechanism before the filling on the filling carrier in the shuttle has been depleted to the de- 40 sired extent, or while the ejected filling carrier or bobbin contains a working supply of filling. In such case, obviously, the amount of waste filling is increased to a most undesirable extent, because the waste filling has 45 already gone through the several processes of its preparation for weaving into cloth, and in addition to the cost of the material itself, and the time in preparing the filling, a large amount of labor loss is also involved.

50 An important feature of the present invention, therefore, consists of means for separating the full from the empty bobbins or filling carriers as they are ejected from the shuttle during the replenishing opera- 55 tion. The terms "full" and "empty" filling

carriers or bobbins are hereinafter used in a general sense, meaning that a full bobbin or filling carrier is one on which there remains when it is ejected from the shuttle, a working supply of filling, and the term empty 60 filling carrier or bobbin meaning one from which the filling has been withdrawn to a degree of substantial exhaustion. By separating the full from the empty bobbins or filling carriers as they are ejected from the 65 shuttle, it becomes possible to return the full filling carriers to the hopper for further use in the shuttle, and to use the filling or yarn still remaining on such filling carrier or bobbin.

In carrying the general features of the invention into practical effect, two receptacles or compartments which may be either formed in a container or separately organized, are provided, one to receive the sub- 70 stantially full, and the other to receive the substantially empty filling carriers or bobbins, and means are provided for permitting the substantially empty bobbins to pass to their receptacle or compartment, and to direct the substantially full filling carriers or bobbins to the other receptacle or compartment.

The above features of the invention and other novel elements and combinations of 75 parts will hereinafter be described in connection with the accompanying drawings which show one good practical form of the invention which, however, is not restricted to the details herein disclosed.

In the drawings:—

Figure 1 is a cross section of a filling re- 80 plenishing loom at the replenishing side thereof, some of the parts being omitted for clearness of illustration;

Fig. 2 is a sectional detail on an enlarged scale showing by full lines the action of the invention when a filling carrier or bobbin having a working supply of filling therein is discharged from the shuttle, and by dotted lines the action when the filling carriers or bobbins have been substantially exhausted of filling; and

Fig. 3 is a detached detail on an enlarged scale showing more particularly features of 100 the invention associated with the guides and receptacles for operating upon the filling carriers.

The loom frame 1 may be of usual character for supporting the operating parts, and 110

is provided with the cross or breast beam 2 from which rises the stand 3 for supporting the hopper 4 which may be of any usual type, but as herein shown is of the rotary 5 class of hoppers. The rotary hopper 4 is provided with means for carrying a supply of filling carriers 5 which contain a working supply of filling and are to be transferred to the shuttle under the direction of the filling 10 replenishing mechanism.

The rotary hopper 4 is provided with the usual ratchet teeth 6 by which it may be given a step movement after each filling replenishing operation to position a filling carrier 15 for transfer. When in transferring position, the filling carrier may rest against the abutment 7 above the passageway or throat 8, and the yielding finger 9 is adapted to be moved downwardly to permit the filling 20 carrier to pass when it is being transferred to the shuttle.

The stand 3 has mounted thereon the stud or shaft 10 on which is supported the transerrer 11 having the downwardly extending 25 arm 12 as usual, provided at its lower end with the pivotally connected dog 13, the end 14 of which is adapted to be engaged by the bunter 15 carried by the lay 16 when the dog is positioned by the filling detecting 30 mechanism, all as usual in this class of looms.

The construction is such that when the transverse shaft 17 mounted on the loom frame and carrying the finger 18 is rocked 35 contra-clockwise (Fig. 1), the dog 13 through the intervening connections is raised to present its end 14 into position for engagement by the bunter 15 as the lay moves frontwardly to thereby effect replenishment of filling. It is not deemed necessary to further explain the details of the filling detecting mechanism or the details 40 of the replenishing mechanism and its operation, as these features may be as usual in this class of looms, and are well understood 45 in the art.

The lay 16 carries the usual shuttle-box 19 at the replenishing side of the loom, and the shuttle-box has the opening 20 through 50 which a filling carrier ejected from the shuttle by the replenishing mechanism may pass. This construction also may be of usual and well understood character.

Mounted on a suitable support or attached 55 to the loom frame, is the container 21 which may be provided with a compartment 22 for receiving substantially full filling carriers or bobbins, and a compartment 23 for receiving substantially empty filling carriers or bobbins as they are ejected from the shuttle by the operation of the filling replenishing mechanism. The compartments 22 and 23 are herein shown as formed as part of the container 21, but while this 60 is a preferred embodiment of this feature

of the invention, the compartments 22 and 23 or receptacles for the full and empty bobbins may be otherwise formed and associated.

The present invention contemplates the provision of means which will permit the empty filling carriers to pass to one of the receptacles or containers, and will direct the substantially full filling carriers or bobbins into the other compartment or receptacle, 70 to thereby separate the two classes of filling carriers, so that those which contain a working supply of filling when discharged from the shuttle, may be conveniently collected and returned to the hopper. The means for separating the full from the empty bobbins or filling carriers may be variously devised, and in the present instance, it is formed as a guide or director which is normally in position to permit the 75 passage of one class of filling carriers or bobbins to their intended receptacle or container, and is moved into position to effect the passage of the other class of filling carriers to their receptacle or container. In 80 the present form of the invention, the container 21 has pivoted thereto at 24 an arm 25 to which is connected the chute 26, and a spring 27 acts upon the arm 25 to normally hold the chute 26 in position for receiving 85 the ejected filling carriers into its upper end portion. In order to conveniently determine the position of the chute 26, a lug 28 on the arm 25 engages a portion of the container 21 which acts as a stop as indicated in 90 Fig. 1.

The chute 26 may be variously formed and may be connected to the container 21 by the means shown and described, or by other means, and is provided with an entrance portion 29 which, is received into an opening 30 formed in the lay below the replenishing shuttle-box when the lay is in substantially its front position, the construction being such that at such times the upper end portion of the chute 26 and the lay and shuttle-box assume the relative positions indicated by Fig. 2.

Mounted in the chute 26 is the means for separating the full from the empty bobbins 115 and directing them in different paths. In the present instance, the chute 26 is provided with the lugs 31 to which is pivotally mounted at 32 the plate 33, which for identification may be known as the deflector. The 120 plate 33 extends longitudinally of the shuttle-box a substantial distance when the parts are in co-operating relation as indicated in Figs. 2 and 3, and a spring 34 normally acts to hold the plate 33 in dotted line 125 position as indicated in Fig. 2. The upper end portion of the deflector 33 is turned or bent rearwardly as indicated in Figs. 2 and 3, at 35, for a purpose that will presently appear. Mounted on the upper por- 130

tion of the chute 26 is a guide or abutment 36 which is supported opposite the upper end portion of the deflector 33. Like the deflector 33 the guide or abutment 36 extends longitudinally of the chute 26, as indicated in Fig. 3, and like the deflector, its end portion at one end of the entrance to the chute, terminates short of the end wall 37 of the chute to provide sufficient space or clearance for the passage of the head or butt ends of filling carriers or bobbins as they pass from the shuttle-box during the replenishment of filling. The guide or abutment 36 has beveled or inclined upper and lower surfaces, as indicated in Figs. 2 and 3, and is adjustably connected to the upper portion of the chute 26. The adjusting means, in the present instance, consists of the threaded bolts 38 and their co-operating nuts 39, the construction being such that the space between the guide or abutment 36 and the upper end portion of the deflector 33, when the latter is in its normal or dotted line position (Fig. 2) may be adjusted to suit conditions of use.

When the parts are in normal position as indicated by dotted lines (Fig. 2), and a filling carrier from which the filling has been substantially exhausted is ejected from the shuttle during the replenishing operation, it will pass downwardly between the abutment 36 and the upper inclined end portion 35 of the deflector, as indicated at *a* (Fig. 3), without tilting or operating the deflector, and will pass downwardly into the receptacle or compartment 23, as indicated at *b*. When, however, the filling carrier that is ejected from the shuttle has a working supply of filling thereon, as indicated at *c* (Fig. 2), it will engage the upper rearwardly turned end of the deflector 33 as it is forced downwardly by the trans-ferrer 11, and swing the deflector from its dotted to its full line position (Fig. 2), thereby inclining the deflector into a position to direct the filling carrier and its working supply of filling into the compartment or receptacle 22, such movement of the deflector being accomplished against the tension of the spring 34.

In order that the deflector 33 may not instantly return to its normal inoperative position, as indicated by dotted lines (Fig. 3) as soon as the filling carrier has passed the pivotal point 32 of the deflector, the latter is provided with holding means for temporarily holding the deflector in its operative position to deflect the filling carrier with the working supply of filling thereon into its proper compartment or receptacle. The holding means may be variously contrived and be tripped by the filling carrier itself as it passes to its intended receptacle or compartment. In the present instance 65 of the invention, the lower end portion of

the deflector 33 has pivotally connected thereto at 40 an arm 41 which extends rearwardly from the pivot 40 and is constituted as a weight, as indicated in Figs. 2 and 3, the construction being such that when the parts are in normal inoperative position, as indicated by full lines (Fig. 1) and dotted lines (Fig. 2), the spring 34 holds the lower end of the deflector, and perforce the arm or weight 41 in the position indicated by full lines (Fig. 1) and dotted lines (Fig. 2). When, however, a filling carrier having a working supply of filling thereon is ejected from the shuttle, and the upper end 35 of the deflector is moved from its dotted to its full line position (Fig. 2), and the lower end thrown outward, as indicated in the drawings, the arm 41 being constituted as a weight, will assume the position indicated by full lines (Fig. 2), and act on the lower end of the deflector to hold it temporarily in its operative position, at which time it will direct the filling carrier into its selected receptacle or compartment. When the arm or weight 41 is in the above described position, it should be stopped in such position that the spring 34 may return the deflector and weighted arm 41 to their normal inoperative position after the full bobbin has passed. To this end the arm 41 may be provided with a pin 42 which rides in an inclined slot 43 formed in the wall of the chute 26, the construction being such that when the deflector 33 is in its operative position (full lines Fig. 2), the pin 42 will rest at the lower end of the slot 43 and thus limit the downward movement of that end of the arm or weight 41.

In order that the spring 34 may assert itself to return the deflector to its inoperative or dotted line position (Fig. 2) after the full filling carrier or bobbin has been directed into its desired receptacle or compartment, the arm 41 has connected thereto a trip 44 which extends into the path of the substantially full filling carrier as it passes toward its receptacle or compartment.

The trip 44 is constituted as a plate pivotally mounted on the lower end of the deflector 33 and appropriately secured to or formed as part of the arm 41, the construction being such that the arm 41 and the trip 44 act in unison.

When a filling carrier contains a substantially exhausted condition of filling thereon when it is ejected from the shuttle, it will pass downwardly into the chute 26, as indicated at *a*, *b* (Fig. 2), and into its intended receptacle 23, while the deflector 33 remains in its normal inoperative position, as indicated by dotted lines in Fig. 2. When, however, a filling carrier which still contains a working supply of filling is ejected from the shuttle by the replenishing mechanism, it will, in passing downwardly between the

abutment 36 and the top portion of the deflector 33, force the top portion of the deflector 35 backwardly, and perforce, move the deflector into operative position, (full lines Fig. 2), where it will be temporarily held by the arm 41, as hereinbefore described, and as the filling carrier containing a working supply of filling passes downwardly toward its receptacle or compartment, it will engage the trip or plate 44 and tilt the plate and the connected arm 41 to permit the spring 34 to return the parts to their normal inoperative position. The chute 26 may have a division wall 45 which 15 may divide the chute into passageways for directing the full and empty bobbins into their appropriate receptacles or compartments.

By mounting the deflector in the yielding chute 26, provision is made for yielding frontward movement of the chute 26 and deflector to accord with the position of the lay, but this construction, of course, while preferable, is not necessary to the proper 25 operation of the invention, and the deflector may be otherwise mounted, the essential in this respect being that it shall serve to separate the full from the empty filling carriers or bobbins as they are ejected from the 30 shuttle.

What is claimed is:—

1. In a filling replenishing loom, the combination of the lay and shuttle, filling replenishing mechanism, a receptacle for receiving substantially empty filling carriers as they are ejected from the shuttle, a second receptacle for receiving filling carriers that contain a working supply of filling when ejected from the shuttle, and means made 35 effective by the ejection of a carrier having a working supply of filling thereon for directing it into the second receptacle.

2. In a filling replenishing loom, the combination of the lay and shuttle, filling 45 replenishing mechanism for ejecting a filling carrier or bobbin from the shuttle and substituting another therefor, a deflector, means normally acting upon the deflector to permit a substantially empty ejected filling carrier 50 or bobbin to pass in one direction, said deflector rendered effective by the ejection of a substantially full filling carrier to deflect the latter in a different direction.

3. In a filling replenishing loom, the combination of the lay and shuttle, filling 55 replenishing mechanism for ejecting a filling carrier or bobbin from the shuttle and substituting another therefor, a deflector, means normally acting upon the deflector to permit 60 a substantially empty ejected filling carrier or bobbin to pass in one direction, said deflector rendered effective by the ejection of a substantially full filling carrier to deflect the latter in a different direction, and different receptacles for receiving the substan-

tially empty and the substantially full filling carriers or bobbins.

4. In a filling replenishing loom, the combination of the lay and shuttle, means for replenishing the filling in the shuttle, and means effective as the bobbins are ejected from the shuttle for directing substantially full bobbins in a different path from the substantially empty bobbins to separate the two. 75

5. In a filling replenishing loom, the combination of the lay and shuttle, a hopper, a transerrer for ejecting a filling carrier from the shuttle and replacing it by one from the hopper, and means by which substantially full filling carriers are permanently separated from substantially empty filling carriers as they are ejected from the shuttle. 80

6. In a filling replenishing loom, the combination of the lay and shuttle, a hopper, 85 means for replenishing the filling in the shuttle from the hopper and ejecting the filling carrier in the shuttle, and means by which filling carriers that have a working supply of filling thereon when ejected from the shuttle are permanently separated from those that do not contain a working supply 90 of filling.

7. In a filling replenishing loom, the combination of filling replenishing mechanism, 95 the lay and shuttle, and means controlled in its position by the amount of filling on the filling carrier when it is being ejected for determining the direction of its movement. 100

8. In a filling replenishing loom, the combination of the lay and shuttle, a hopper for supplying filling carriers wound with filling, means for ejecting the filling carrier in the shuttle and substituting for it a filling carrier from the hopper, a receiver having two receptacles, and means for directing the ejected filling carrier into one of said receptacles when it contains a working supply of filling and permitting it to pass to the other receptacle when the filling on the ejected carrier is substantially exhausted. 105

9. In a filling replenishing loom, the combination of the lay and shuttle, a hopper, a transerrer for transferring filling carriers from the hopper to the shuttle and ejecting the carrier that is in the shuttle, a receptacle for receiving the ejected filling carriers from which the filling has been withdrawn to a degree of substantial exhaustion, a second receptacle for receiving the ejected filling carriers from which the filling has not been withdrawn to a degree of substantial exhaustion, and means for directing the last named filling carriers into the second receptacle. 115

10. In a filling replenishing loom, the combination of the lay and shuttle, means for replenishing the filling in the shuttle, different receptacles for receiving ejected fill- 120

ing carriers, and means by which filling carriers that have a working supply of filling thereon when ejected from the shuttle are directed into a different receptacle from that 5 which receives the filling carriers which do not contain a working supply of filling when ejected from the shuttle.

11. In a filling replenishing loom, the combination of the lay and shuttle, filling 10 replenishing mechanism, two receptacles, one for receiving substantially exhausted filling carriers and the other for receiving filling carriers which still contain a working supply of filling when they are ejected from the 15 shuttle, and a deflector for directing the latter filling carriers to the other receptacle as they are ejected from the shuttle.

12. In a filling replenishing loom, the combination of the lay and shuttle, filling 20 replenishing mechanism, a container having a compartment for receiving substantially exhausted filling carriers and a second compartment for receiving filling carriers that have a working supply of filling thereon 25 when ejected, and means for directing the last named filling carriers into the second compartment.

13. In a filling replenishing loom, the combination of the lay and shuttle, filling 30 replenishing mechanism, a normally inoperatively positioned deflector below the lay for directing full filling carriers or bobbins into a different path from that followed by the empty filling carriers, and actuated by 35 a full filling carrier or bobbin as it is ejected from the shuttle for operatively positioning the deflector.

14. In a filling replenishing loom, the combination of the lay and shuttle, filling 40 replenishing mechanism, a normally inoperatively positioned deflector below the lay for directing full filling carriers or bobbins into a different path from that followed by the empty filling carriers, and actuated by 45 a full filling carrier or bobbin as it is ejected from the shuttle for operatively positioning the deflector, and means for holding the deflector in operative position.

15. In a filling replenishing loom, the combination of the lay and shuttle, filling 50 replenishing mechanism, a normally inoperatively positioned deflector below the lay for directing full filling carriers or bobbins into a different path from that followed by the empty filling carriers, and actuated by 55 a full filling carrier or bobbin as it is ejected from the shuttle for operatively positioning the deflector, and means projecting into the path of the full filling carrier for temporarily holding the deflector in its deflecting 60 position.

16. In a filling replenishing loom, the combination of the lay and shuttle, filling 65 replenishing mechanism, a normally inoperatively positioned deflector below the lay

for directing full filling carriers or bobbins into a different path from that followed by the empty filling carriers, and actuated by a full filling carrier or bobbin as it is ejected from the shuttle for operatively positioning 70 the deflector, and means projecting into the path of the full filling carrier for temporarily holding it in deflecting position, and a spring for returning the deflector to inoperative position. 75

17. In a filling replenishing loom, the combination of the lay and shuttle, filling 80 replenishing mechanism, a deflector pivotally mounted below the lay, a spring normally acting to hold the deflector in inoperative position and adapted to yield to permit the deflector to be operatively positioned by a substantially full filling carrier as it is ejected from the shuttle, means for holding the deflector in its operative position and 85 adapted to be tripped by the substantially full filling carrier to permit the deflector to return to its inoperative position.

18. In a filling replenishing loom, the combination of the lay and shuttle, filling 90 replenishing mechanism, and a deflector below the lay for separating the substantially full from the substantially empty filling carriers as they are ejected from the shuttle.

19. In a filling replenishing loom, the combination of the lay and shuttle, filling 95 replenishing mechanism, and a movable deflector actuated by passing filling carriers as they are ejected from the shuttle for separating filling carriers that contain a working supply of filling from those that are substantially exhausted of filling. 100

20. In combination with a filling replenishing loom having a lay and shuttle, a receptacle for receiving the ejected filling carriers, and means movably mounted upon the receptacle and constructed to receive the ejected filling carriers and to separate the full from the empty filling carriers, said separator means constructed to be engaged 105 by the lay and held thereby in alignment with the shuttle during the ejecting of a filling carrier from the shuttle. 110

21. In a filling replenishing loom, the combination of the lay and shuttle, filling 115 replenishment mechanism, a receptacle for receiving the ejected filling carriers, a chute for the ejected filling carriers movably mounted upon the receptacle and constructed to be engaged by the lay and held thereby in alignment with the shuttle during the ejecting of a filling carrier, and a deflector within 120 said chute for separating the substantially full filling carriers from the substantially empty filling carriers as they are ejected 125 from the shuttle.

In testimony whereof I have signed my name to this specification.

MELVIN L. STONE.
